(57) CLAIM

We claim the ornamental design for a display screen or portion thereof with icon, as shown and described.

DESCRIPTION

The file of this patent contains at least one drawing executed in color. Copies of this patent with color drawing(s) will be provided by the Office upon request and payment of the necessary fee.

FIG. 1 is a front view of a display screen or portion thereof with icon in accordance with a first embodiment of the invention; and,
FIG. 2 is a front view of a display screen or portion thereof with icon in accordance with a second embodiment of the invention. This embodiment is a color version of the first embodiment.

The broken line in each figure depicts the display screen or portion thereof for the purpose of illustrating environment and forms no part of the claimed design.
